(57) **CLAIM**

The ornamental design for a bra, as shown and described.

DESCRIPTION

FIG. 1 is a front view of a bra showing my new design; FIG. 2 is a rear view thereof;

FIG. 3 is a perspective view showing a first configuration of use;

FIG. 4 is a perspective view showing a second configuration of use;

FIG. 5 is a left side view thereof;

FIG. 6 is a right side view thereof;

FIG. 7 is a front view of the bra in FIG. 3;

FIG. 8 is a front view of the bra in FIG. 4;

FIG. 9 is a rear view of the bra in FIG. 3;

FIG. 10 is a rear view of the bra in FIG. 4; and,

FIG. 11 is a rear view showing a third configuration of use. The broken lines in the drawings depict portions of the bra that form no part of the claimed design. The broken lines in the drawings illustrating the environmental subject matter form no part of the claim.

1 Claim, 11 Drawing Sheets
